(57) **CLAIM**

The ornamental design for a watch, as shown and described.

DESCRIPTION

FIG. 1 is a front view of a watch showing the new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front, right, and top perspective view thereof; and,

FIG. 8 is a rear, left, and top perspective view thereof. The broken lines in the drawings illustrate portions of the watch that form no part of the claimed design.
